UNITED STATES PATENT OFFICE.

ELMER E. HAUER, OF SPRINGFIELD, OHIO, ASSIGNOR, BY MESNE ASSIGNMENTS, TO ELLIOTT COMPANY, OF PITTSBURGH, PENNSYLVANIA, A CORPORATION OF PENNSYLVANIA.

ROTARY MOTOR.

1,185,200.

Specification of Letters Patent.

Patented May 30, 1916.

Application filed December 16, 1914. Serial No. 877,492.

To all whom it may concern:

Be it known that I, ELMER E. HAUER, a citizen of the United States, residing at Springfield, in the county of Clark and State 5 of Ohio, have invented certain new and useful Improvements in Rotary Motors, of which the following is a specification, reference being had therein to the accompanying drawings.

10 My invention relates to rotary motors and more particularly to a motor for driving tube cleaners that is adapted to travel through a tube with the cleaner, although it may be used for other purposes.

15 The object of my invention is to provide a simple and efficient motor of few parts that will be durable in the severe service for which it is particularly designed.

A further object is to provide improved 20 means for securing the rotary motor member to its shaft.

A further object is to provide improved bearings that will both carry and take the end thrust of the shaft.

25 With these and other objects in view my invention consists of the constructions and combinations hereinafter described and set forth in the claims.

In the accompanying drawings which 30 form a part of this specification Figure 1 is a longitudinal section partially in elevation of a motor embodying my invention and Figs. 2 and 3 are cross-sections taken on the line 2—2 and 3—3 respectively of Fig. 1.

35 In the drawings a body or casing having a supply head 1 with forwardly projecting cylinders 2 and 3 and a cross-partition 4 within the inner cylinder 3 is preferably formed integrally as shown. The inlet 5 of 40 the supply head opens into the inner cylinder 3 and an opening 6 through the longitudinal wall of said cylinder admits the motive agent to an annular chamber 7 formed between the cylinders 2 and 3. The inner

45 cylinder 3 is shorter than the outer cylinder 2 and the bore is enlarged at 8 as shown.

A ported partition 9 may be secured in any suitable way to form the front wall of the annular chamber 7 but is shown as

50 screw-threaded at 10 to the inner cylinder.

A rotary motor member 11 having a rearward extension 11^a projecting through an opening 9^a of the ported partition and which is shown in the form of a turbine having

55 buckets 12 operates within a motor chamber 13 formed by the enlarged bore 8 of the outer cylinder. Said rotary motor member is further provided with a forward extension 14 with a recess 15 therein extending from its front end; and said member is 60 keyed to a shaft 16 by a key 17 and is tightened and held against a shoulder 18 of the shaft by a nut or holding member 19 on the screw-threaded end 20 of said shaft. The recess 15 is screw-threaded as shown for the 65 attachment of the tool to be driven.

The inner cylinder 3 forms a bearing chamber into which the shaft 16 projects and is journaled in oppositely disposed anti-friction bearings. These bearings are of 70 like construction and a description of one will answer for the other. In Fig. 1 of the drawings the cage for the forward bearing is shown in section and for the rear bearing it is shown in elevation. The shaft 16 is 75 provided with inclined shoulders 21 for each of the bearings and preferably between said shoulders and the cylindrical portions 22 of the shaft on which the rollers are seated grooves 23 are provided to facilitate the 80 grinding of said cylindrical portions. Cages 24 having beveled ends 25 are provided with longitudinal slots 26 in which rollers 26 having beveled or inclined ends 27 are seated.

A divided bushing 28, the respective portions of which are screw-threaded together at 29, is provided at its outer ends with inclined shoulders 30 and is fitted within the bearing chamber. 85

The rollers and their beveled or inclined 90 ends extend beyond the surface of the cages and operate between the cylindrical portions of the shaft and bushing, the beveled or inclined ends of the rollers being seated between the inclined shoulders of said shaft or 95 bushing, the arrangement being such as to both carry and take the end thrust of said shaft.

The cages with the rollers therein are placed upon the shaft and lugs 31 of the 100 cages are then bent over shoulders on the shaft as shown to hold the cages in place on the shaft.

By means of the screw-threaded connection 29 of the respective parts of the bushing 28 the bushing shoulders are adjusted 105 and held in their relation to the rollers and the shaft shoulders. The bushing with the

bearings therein is then slipped within the bearing chamber and tightened and held in place by the ported partition 9.

Lubricant is supplied to the bearing chamber through a passage 32 in the shaft and a plug 33 is provided at the outer end of said passage. A packing 34 between the front end of the bushing and the ported partition and abutting the rear extension of the rotary motor member prevents leakage of the motive agent into the bearing chamber.

Having thus described my invention I claim—

1. In a rotary motor, a casing or body open at its front end and having a central rearwardly extending bearing chamber closed at its rear end, means introduced through said front end to form a ported partition and close the front end of said chamber, a rotary motor member having a shaft projecting through an opening in said partition into said bearing chamber, said shaft having an inclined shoulder, a bushing fitted in said chamber and having an inclined shoulder, longitudinally extending rollers between said shaft and bushing and between said shaft shoulder and bushing shoulder, the ends of the rollers being inclined to conform to the inclination of the respective shoulders and means to conduct the motive agent to said ported partition, substantially as described.

2. In a rotary motor, a casing or body open at its front end and having a central rearwardly extending bearing chamber closed at its rear end, means introduced through said front end to form a ported partition and close the front end of said chamber, a rotary motor member having a shaft projecting through an opening in said partition into said bearing chamber, said shaft having cylindrical portions with inclined shoulders, a bushing fitted in said chamber and having inclined shoulders, longitudinally extending rollers between said cylindrical portions and bushing and between said shaft and bearing shoulders, the ends of said rollers being inclined to conform to the inclination of the respective shoulders, said bushing being arranged

to adjust and hold said shoulders in proper relation to said rollers and means to conduct the motive agent to said ported partition, substantially as described.

3. In a rotary motor, a casing or body having a motor chamber with fluid supply openings thereto and a bearing chamber, a rotary motor member in said motor chamber having a shaft projecting into said bearing chamber, said shaft having cylindrical portions with inclined shoulders, a bushing fitted in said bearing chamber and having inclined shoulders, longitudinally extending rollers between said cylindrical portions and bushing and between said shaft and bushing shoulders, the ends of said rollers being inclined to conform to the inclination of the respective shoulders, said bushing being arranged to adjust and hold said shoulders in proper relation to said rollers and means to hold the same in adjusted position within said bearing chamber, substantially as described.

4. In a rotary motor, a casing or body having a motor chamber at its front end and a bearing chamber extending rearwardly therefrom, a rotary motor member having a rearward extension projecting into an opening in the rear wall of said motor chamber and having a shaft journaled in said bearing chamber, substantially as described.

5. In a rotary motor, a casing or body having a motor chamber at its front end and a bearing chamber extending rearwardly therefrom, a rotary motor member having a forward extension adapted to attach the tool to be driven and a rearward extension projecting into an opening in the rear wall of said motor chamber and a shaft journaled in said bearing chamber, substantially as described.

In testimony whereof I have hereunto affixed my signature in the presence of two witnesses.

ELMER E. HAUER.
